(57) **CLAIM**

The ornamental design for a vehicle mirror, as shown and described.

DESCRIPTION

The Vehicle Mirror shown and described herein is similar to the vehicle mirrors shown and described in the following design applications filed on even date herewith: Design application Ser. No. 29/321,843; Design application Ser. No. 29/321,841; Design application Ser. No. 29/321,832; and, Design application Ser. No. 29/321,829, all filed on Jul. 24, 2008.

FIG. 1 is a front view of a left vehicle mirror;

FIG. 2 is a top view of a left vehicle mirror;

FIG. 3 is a bottom view of a left vehicle mirror;

FIG. 4 is a back view of a left vehicle mirror;

FIG. 5 is a left side view of a left vehicle mirror;

FIG. 6 is a right side view of a left vehicle mirror; and,

FIG. 7 is a perspective view of a left vehicle mirror.

The second embodiment is a mirror image of the left vehicle mirror shown in FIGS. 1-7 and is not illustrated.
